UNITED STATES PATENT OFFICE.

HENRY CAMPBELL, OF BALTIMORE, MARYLAND, ASSIGNOR TO KEYSTONE CORK SEAL COMPANY, OF PHILADELPHIA, PENNSYLVANIA, A CORPORATION OF NEW JERSEY.

BOTTLE-STOPPER.

SPECIFICATION forming part of Letters Patent No. 721,541, dated February 24, 1903.

Application filed April 30, 1902. Serial No. 106,331. (No model.)

To all whom it may concern:

Be it known that I, HENRY CAMPBELL, a citizen of the United States, residing at Baltimore city, State of Maryland, have invented 5 new and useful Improvements in Bottle-Stoppers, of which the following is a specification.

My invention has for its object to furnish a secure air and gas tight stopper or seal for bottles and other vessels which also serves 10 to efficiently protect the usual metallic cap from the action of acids and alkalies present in the contents of the bottles and also to keep the contents of the bottles unaffected by the metal cap.

Heretofore much difficulty has been encountered in the bottling of soft drinks—such as ginger-ale, lemon-soda, &c.—containing acids and held under considerable pressure, such pressure acting to force the acid gases 15 into contact with the metal cap. The latter is originally thin and is soon oxidized and acid-eaten and weakened to such an extent as to leak and render the contents of the bottle valueless. To obviate this, it has been 20 necessary in the case of all bottling of such goods which are not to be consumed within a short time to abandon the inexpensive cap and seal and return to the former method of bottling with long corks. This involves much 25 expense, especially in the export trade. It has been attempted to remedy this difficulty by coating the metal caps with shellac, paraffin, and various substances or by placing 30 within them disks of paper similarly treated; but these remedies have not proved efficient 35 to protect the cap from the action of acids and leakage, as above described.

By my invention I not only cause the compression and sealing to be more efficient, but 40 I provide an acid-proof protection for the cap at a distance from the latter, yet not in contact with the bottle contents to affect the color or taste of the latter.

The invention consists, primarily, in a metal 45 cup-shaped cap or crown having therein a plurality of layers or disks of cork, with an interposed layer or disk of other material.

It further consists in the parts and combinations thereof hereinafter set forth.

50 In order to make the invention more clearly

understood, I have shown in the accompanying drawings means for carrying the same into practical effect without limiting my improvements in their useful applications to the particular constructions which for the sake 55 of illustration I have delineated.

In said drawings, Figure 1 shows a vertical central sectional view of the neck of a bottle sealed according to my invention. Fig. 2 is a bottom plan view of the stopper and cap, 60 portions of the stopper being broken away. Fig. 3 is a vertical sectional view of the stopper before application. Figs. 4, 5, and 6 are plan views of the upper, intermediate, and lower disks of the stopper, respectively. 65

Referring to the drawings, 1 is a bottle, of which the rounded lip of the mouth is shown at 2. The bottle has near the mouth an exterior enlargement or bead 3. My invention is not limited to any particular form or character of such enlargement, so that it serves 70 as a means to properly secure the cap. The latter is shown at 4, having a top 5 and a depending flange or other securing means 6. The latter engages below the enlargement 3, 75 being preferably bent into such position by spinning while under downward pressure against the bottle-mouth.

The stopper proper consists of two or more separate and independent layers or disks 78 80 of cork, a suitable thickness for which disks is from one-sixteenth to one-eighth of an inch. 9 is a layer or disk of different material acid-proof in character, such as paraffin or fibrous material or fabric impregnated with 85 paraffin or like substance. I may also employ for the layer or disk 9 a lining of the nature described in Patent No. 691,382 to H. A. Hughes, dated January 21, 1902, or a composition such as is described in Patent No. 90 691,383 to the same patentee, of the same date. The layer or disk 9 is interposed between the cork disks below the disk 7, which keeps it out of contact with the cap, and above the disk 8, which separates it from the contents of the bottle. The two cork disks form 95 elastic and cushioning means between which the disk 9 is strongly compressed when the cap is applied, but yieldingly in such manner as not to be cracked or thinned, so as to allow 100

the passage of gas or liquid. This stopper has an important function in connection with the application of the cap by pressure to effect a tight seal. As the capping-tool 5 secnds and compresses the stopper between the top 5 and lip 2 the several cork layers yield laterally in different degree, having in effect a sliding movement on each other, which is promoted by the presence of the interposed smooth-surfaced disk 9. Ultimately 10 the disks are drawn individually to a feather-edge against the lip 2, the edge of the lower cork disk 8 extending out a little beyond the edge of the upper disk 7, which, however, is also thinned out at its edge. 15

The above-described construction of the stopper enables its edge as a whole to be drawn out and down to a thin and dense sealing edge held under great compression.

20 While a thick cork disk may be broken or cracked by being bulged down in the middle and stretched out at the edge in the process of application of the stopper under heavy pressure, a thin disk may yield more readily 25 without fracture. Also where two distinct disks are employed one may crack through some imperfection while the other remains intact, and the latter will act to occlude the bottle-mouth, while the edges of both disks 30 serve in making the gas-tight seal around the edge of the bottle-mouth. Moreover, when the disk 9 is made of a fabric, as already described, the fibers of such fabric will lie in planes parallel with the faces of the 35 cork disks and the stretching action, due to the bulging down of the stopper as a whole and the drawing out of its edges, will be in the directions of the length of such fabric fibers. The fabric will thus strongly resist 40 disruption and greatly strengthen the cork disks, especially the upper disk, and even if both disks should crack in the middle the fabric, made impervious to liquid, as described, will keep the stopper tight at the 45 middle, and the heavily-compressed rims of the cork disks will keep the stopper gas-tight at the edge around the bottle-mouth.

I am aware that composite drive-corks have been heretofore proposed, made of a plurality of cork sections cemented together, as 50

shown in patents to Davison, No. 40,742, dated December 1, 1863, and Nageli, No. 650,021, dated May 22, 1900, and I do not claim the same as my invention; but I believe myself to be the first to combine with such a cap as that shown at 4 a plurality of cork disks capable of separately yielding to pressure and stretching individually at their edges and also the first to combine with such a cap a cork disk within the cap and below the disk on the side thereof next to the bottle a disk of fabric having its fibers in the planes of the stretching and disrupting strains and adapted to resist such disruption and to support the cork disk. 65

What I claim is—

1. In a stopper or seal for bottles, the combination of a plurality of layers or disks of cork, with a loosely-interposed layer or disk of other material, and a metallic cap containing said disks and having its lower part adapted to be bent to engage a bottle and hold said disks compressed on the bottle-mouth. 70

2. In a stopper or seal for bottles, the combination of an upper disk of cork, a lower disk of cork, an interposed disk of other material arranged to leave the opposing faces of said cork disks laterally movable one with respect to the other for independent yielding or stretching as they are applied to the rim of a bottle-mouth, and a metallic cap having its lower part adapted to be bent to engage with a bottle and hold said disks compressed on the bottle-rim. 80

3. In a stopper or seal for bottles, the combination of a plurality of layers or disks of cork, with a loosely-interposed layer or disk of other material, a bottle having an exterior enlargement or bead, and a metallic cap having its lower part bent to engage beneath said enlargement, said layers being separately compressed on the rim of the bottle-mouth by said cap. 85

In testimony whereof I affix my signature in presence of two witnesses. 95

HENRY CAMPBELL.
